SALEM T. LAMB AND GEORGE A. RANKIN, OF NEW ALBANY, INDIANA.

Letters Patent No. 95,236, dated September 28, 1869.

IMPROVEMENT IN PEDDLERS WAGON.

The Schedule referred to in these Letters Patent and making part of the same.

To all whom it may concern:

Be it known that we, SALEM T. LAMB and GEORGE A. RANKIN, of New Albany, in the county of Floyd, and State of Indiana, have invented certain new and useful Improvements in Peddlers' Wagons; and we do hereby declare the following to be a full, clear, and exact description of the construction and operation of the same, reference being had to the accompanying drawings, making a part of this specification, in which—

Figure 1 represents a perspective view of the body of the wagon, the running gear being omitted, and with the side doors open, or partially so, to show the interior, the view being taken from the front, toward the rear of the wagon-body.

Figure 2 represents a perspective view of a portion of the wagon-body, looking from the rear thereof, and representing one of the rear doors as thrown open to show the interior of the body at this point or part of it.

Figure 3 represents, in perspective, a folding bench, stand, or counter, detached from the wagon, but carried by it, as and for a purpose that will be explained.

There are several conditions and necessities in and about a peddler's wagon, which it has been our object and purpose to improve:

First, that the goods carried therein should be perfectly protected from the rain;

Second, that they may be carried about without being damaged by the transportation;

Third, that they should be comparatively secure from depredations;

Fourth, that they should be so classified, and assorted, and kept, as that they may be of easy access at all times;

Fifth, that they may be displayed with readiness and convenience; and

Sixth and finally, that the user, who may be said to live in his wagon, may carry his wardrobe, be protected from the elements, and also carry with him such implements as his team may require in properly caring for it.

These conditions and necessities require an economy of arrangement and space, in and about the wagon, and a construction of parts, that constitute the gist of our invention.

To enable others skilled in the art to make and use our invention, we will proceed to describe the same with reference to the drawings.

The body of the wagon is composed of three sections or members, A B C, which, though united into one, may be separately described, as follows:

The front section or member A has, underneath the foot-board *a*, two apartments, *b b*, access to which is had through the hinged doors *c c*.

Underneath the apartments *b b*, and under the floor or bottom of the wagon-body *d*, there is an apartment, *e*, access to which is had by the door *f*; and this apartment may be divided into two by a partition, and is designed for curry-comb, brush, horse-blankets, and other articles used for grooming horses. *g* is the dash-board.

The middle section or member B has in it a series of apartments, *h*, formed by the shelves *i*, which, together with those, *b b*, in section A, are designed for such goods as peddlers carry and deal in.

The apartments *h* are closed by a door, *j*, and access had to them by said door, which can be securely locked.

Above the apartments *h* is the salesman's and driver's seat *k*, and the back of the seat, or that which supports the backs of the occupants of the seat, is an apartment, with doors or covers *l*, and may be used for containing the wardrobe of the owner or driver, as it is under the swinging top *m*, and hence completely shielded from the weather.

The top *m*, (of which we have shown the frame only, omitting the cover,) is a material portion of the section or member B, of which it is a part.

The front, rear, and central bows 1, 2, 3, are pivoted to a stud, *o*, at each side of the wagon or seat-part thereof, and the intervening bows 4 5 are pivoted to the central bow 3, at the point C.

The front, central, and rear bows 1, 3, 2, are connected to each other and to a stem or post, 7, attached to the body of the wagon, by means of the pairs of toggle-levers 8, 9, 10, and to the toggle-joints of each of these pairs of toggle-levers is pivoted one end respectively of the connecting-bars 11, 12, 13, the other ends of which are pivoted at different points along or on a hand-lever, 14, that is pivoted and swings on the post or stud *o*.

By taking hold of the hand-levers 14, (there being one at each side or end of the seat,) the top can be raised and held up, the holding being done by the toggles passing below a line drawn through their pivoted points on the bows, or let down at pleasure, and with the greatest facility and ease to the operator, the system of levers and of hanging or hinging the several parts being so arranged as to operate at all points simultaneously and with the most available use and power of the lever-connections.

n n are the stay-straps for holding the bows in proper position when elevated.

The section or member C of the body has a series of shelves, *p p*, which make a series of apartments, *q*, all of which are protected and secured by a door, *D*.

Behind these apartments, and accessible by the hinged doors *E E*, is a series of drawers, *r r r*, separated by a vertical partition, *s*, against which the

doors E E close, and so that either tier of drawers may be readily got at.

These drawers may be used for carrying the finer qualities of goods, and such as are better kept assorted and separated.

The hinges t t, by which the doors E are hung, have curved leaves, so that while each door can fit in closely when shut, it may, when opened, swing clear of the corner of the body, and lie close to its sides, and thus make free space for sliding the drawers out or in.

The section C is roofed with a rounded roof, impervious to rain, and the joints of the panels are covered by metallic strips u.

It should have been stated of the shelves and apartments in the sections, that they only extend half way across the body, there being a similar series on the opposite side, arranged and protected in a similar way.

This way of dividing the apartments centrally of the body in its longitudinal line, not only makes them more readily accessible from the sides, but it admits of a central longitudinal frame-work in the body, without which it would scarcely hold its load; and this central frame-work supports the ways v, on which the drawers r run, and which ways and partition constitute or are a part of the longitudinal central frame of the body.

Under the sections B and C of the body is hung, one on each side of the wagon, a swinging counter, F, on which the goods may be laid for inspection, or for convenience of measuring or selling.

This counter is suspended from the body underneath by suspending-bars w w, pivoted to both counter and body, so that by drawing out the counter it will drop down, as shown in fig. 1, and by pushing it in, it will rise up against the bottom of the body, and then, by turning the fastenings x x, which swing under keepers under the body, it will be held there.

At the rear of the body of the wagon there is a case or cage, y, into which can be slipped and there carried a folding or fold-up bench, G, fig. 3, which is designed for the seller or buyer, or both, to stand up so as to reach or look into the upper tiers of drawers, shelves, or apartments.

The legs or supports z of this bench are hinged so as to fold up, as seen to the left of fig. 3, or to be swung out and braced by the hinged braces a' a', which have catches to make them rigid when out, but so also as to fold up with said supports when they are folded up.

The spring b' on said bench is to catch and hold it in or against the case or cage to prevent it from dropping out accidentally, by the jar of the wagon.

For giving strength to this structure, and especially that portion of it where the drawers r are arranged and carried, the contents of which are heavy, we arrange and secure the panels in a vertical position, which is the direction in which the main strain comes, and thus the panels strengthen the structure very much.

We have shown a convenient way of suspending and carrying the counter and fold-up bench, but do not limit ourselves to this exact plan. So long as we carry and use these appliances in connection with a peddler's wagon, and were the first to so apply and use them, we claim them as our invention.

Modifications may and no doubt will be made in our construction of peddlers' wagons, with a view of evading our rights; but so long as the general characteristics of our structure are preserved, we shall claim such mere changes as involving our invention.

Having thus fully described our invention, What we claim therein as new, and desire to secure by Letters Patent, is—

1. The construction and arrangement of the wagon-body, viz., of the three sections or members, with their shelves and apartments protected, and accessible by means of hinged doors at the sides and ends, substantially as and for the purpose described.

2. Also, in combination with the driver's seat, a rising and falling top that is connected through toggle-levers and bars to lifting-levers in convenient position to the occupant of said seat, so that said occupant may raise and hold up or let down said top at pleasure, substantially as described.

3. Hanging the doors E to the body of the wagon by hinges having curved leaves, so that said doors may swing close into the frame when shut, and entirely out of the way of the sliding drawers when opened, as set forth and explained.

4. Also, in combination with the body of the wagon, the swinging counter, connected and suspended thereto, as and for the purpose described.

5. Also, in combination with the body of the wagon and with a fold-up bench, the case or cage, or its equivalent, for containing and carrying said hinged or fold-up bench, as and for the purpose described.

6. Also, in connection with the seat and top, the apartment under or at l, for clothes, as described:

SALEM T. LAMB.
GEORGE A. RANKIN.
